UNITED STATES PATENT OFFICE.

EUGENE SCHIMPFF, OF SCRANTON, PENNSYLVANIA.

HEADLIGHT REFLECTOR.

Application filed April 23, 1926. Serial No. 104,000.

This invention relates particularly to a reflector for use on automobile headlights, and aims to provide an improved reflector in which the illuminating efficiency of the beam will be maintained to the fullest extent, but in which objectionable glare will be eliminated.

This object is attained by providing a parabolic reflector in which the lower half 10 of the reflector is provided with a series of surfaces following a parabolic curve in the direction of the axis of the beam and tilted at an angle away from the central axis of the beam.

15 While I have disclosed a preferred embodiment for purposes of illustration it should be understood that various changes in the structure may be made without departing from the spirit and scope of the invention 20 as hereinafter described and claimed.

In the drawings:

Fig. 1 is a front elevation of the reflector; Fig. 2 is a section on line 2—2 of Fig. 1; Fig. 3 is a detail view taken along line 25 3—3 of Fig. 1;

Fig. 4 is a front elevation of a modification;

Fig. 5 is a section on line 5—5 of Fig. 4.

The reflector is of general parabolic shape 30 and it will be clear from Figs. 1 and 2 that the upper half of the reflector 10 is in the form of a true parabola. The rays of light that cause the glare from a headlight are those reflected from the lower half of the 35 ordinary parabolic reflector. In order to eliminate the glare in the present invention the lower half of the reflector is formed into a series of steps flat in a direction circumferential of the reflector, but retaining their parabolic curve in the direction of the axis 40 of the beam. The lower right-hand step 12 is disposed at an angle so that it slopes toward the right away from the center line and is connected by a riser 17 to the step 13.

This step is also set at an angle so that it slopes away toward the right and is connected by a riser 17 to step 14. The steps 14, 15 and 16 are similarly disposed, except that the last step 16 merges into the parabolic surface 10.

The lower left-hand portion of the reflector is formed in the same manner as the right-hand portion just described except that each step slopes toward the left.

As a result of having these flat steps sloping towards the right and left the rays which would ordinarily be thrown forward into the eyes of an approaching driver to produce glare are thrown sharply off to the side or upward in such a manner that they cannot 55 cause annoyance to an approaching driver, while the short relatively perpendicular risers cannot produce any glare.

In the modification illustrated in Fig. 4 a similar result is attained by providing the 65 lower half of the reflector with a series of radially extending ridges which follow the parabolic curve of the reflector. The top of each ridge 17^a after extending a short distance is depressed as at 18 to form two branch 70 ridges 19. By this construction the outer part of the lower half of the reflector is still further broken up and the dispersive effect thereby increased.

I claim:

A short-focus headlight reflector having its upper half formed with a smooth parabolic surface, its lower half being formed with a plurality of relatively narrow steps, the steps being flat circumferentially of the reflector 80 and extending outwardly from the center of the reflector, the upper edge of each step lying in a continuation of the parabola, the lower edge of each step being elevated above the continuation of the parabola.

85 In testimony whereof I affix my signature.

EUGENE SCHIMPFF.
